JOE J. ETTINGER, OF WARSAW, INDIANA, ASSIGNOR TO ZIMMER MANUFACTURING COMPANY, OF WARSAW, INDIANA, A CORPORATION

SURGICAL SPLINT

Application filed February 27, 1930. Serial No. 431,930.

The invention relates to surgical splints and it is particularly directed to the type of splint commonly known as the abduction humerus splint, wherein there is a base or 5 body engaging support and an arm support carried by the base.

Heretofore the base or body support has been straight longitudinally and curved transversely in order that it may be engaged 10 on the side of the trunk of the patient, and the arm support projects outwardly and downwardly from the base. It has been found that the base frequently creeps on the patient's body notwithstanding it is strapped 15 to the body. The angle between the arm support and the base has also been fixed in prior devices so that there could be no angular adjustment of the support relatively to the base.

The object of my invention is to provide 20 a novel base or body-engaging support that is form fitting and will remain in position when applied to the human body. Another object is to provide an arm support that is angularly adjustably carried by the base. 25 Another object is to provide a novel angular arm rest attachable to the arm support and reversible thereon for either right or left arm.

The invention is illustrated in the accompanying drawing in which

30 Figure 1 is a plan view of a splint embodying the invention; Fig. 2 a front elevational view of the splint; Fig. 3 an enlarged side view of the splint with the arm rest removed; Fig. 4 a plan view of the arm rest, 35 and Fig. 5 a side view of the arm rest.

Referring to the illustrative embodiment of 40 the invention, I represent the base or body-engaging support. Preferably the base is formed of aluminum and lined on its inside with felt 2 or other suitable padding material. The base is curved or convex transversely and its middle portion 3 is concaved from its upper edge toward the lower edge 45 thereof with the lower part 4 of said middle portion somewhat convex so as to fit over the hips of the patient. The concave portion or wall 3 and the convex portion 4 conform to the general shape of the body to which the base is applied. The central portions of the 50 opposite lateral ends of the base are prefer-

ably cut out as shown at 5 to reduce the weight of the splint and ventilate the article, and also causing the splint to be more comfortable. Buckles or other fasteners 6 are suitably secured to the lateral ends of the base for the 55 reception of bands or straps which are extended around the trunk of the patient to secure the base in position. Other buckles or fasteners 7 are laterally adjustably mounted on the opposite sides of the upper portion of 60 the base to which a strap or band may be attached and extended over the shoulder at the opposite side of the body. The members 7, being laterally adjustable on the base, may be positioned so that the strap or band attached to them will exert its pull on the base 65 at the correct angle.

A bar 8 is secured to the concaved middle portion 3 of the base. A bar 9 is hinged to the upper end of the bar 8 and a longitudinally slotted bar 10 is hinged to the lower end of said bar 8. The bar 9 is secured to the upper end of a laterally concaved support 11, having the longitudinal slots 12 therein, two slots being shown upon each side of the bar 75 9. A longitudinally slotted bar 13 is hinged to the lower end of the bar 9 and underlies the bar 10. The bolts 14 extend through the alined slots in the bars 10 and 13 and thumb nuts 15 on the bolts serve to clamp the latter 80 bars together in any longitudinally adjusted position of said bars. It is evident that by adjusting the bar 13 longitudinally on the bar 10 the inclination of the support 11 may be adjusted to the desired angle relatively to 85 the base.

A reversible arm rest 16 is attachable to the support 11. This rest is of peculiar form. In general it is V-shaped longitudinally and concaved transversely and it tapers somewhat laterally from its middle portion toward its opposite ends. One side wall 17 is higher than the opposite wall and is highest in its middle portion or at the angle of the arm. The middle portion or angle of the rest 95 is curved transversely so as to form a longitudinally convex surface 18 which is also concave transversely upon which the side of the elbow of the human arm may rest when the arm is bent in normal manner at the elbow. 100

Two transverse slots 19 are formed in each end portion of the rest and are adapted to be registered with the slots 12 in the support 11, that is, with the outer slot 12 on either side 5 of the bar 9 and with the inner slot 12 on the opposite side of said bar. Hence when either arm of the rest 16 is attached to the support 11 by the bolts 20 that are inserted through the registered slots 12 and 19, thumb 10 nuts (not shown) being disposed on the bolts, this arm is in an oblique position on the support 11 and the other arm of the rest extends downwardly and inwardly and it is also oblique to the longitudinal axis of the support 15 11 but in a direction opposite to the obliquity of the attached arm of the rest 16. In Figs. 1 and 2 the rest 16 is installed for use on the right arm. The transverse slots 19 are of sufficient length to permit of lateral adjustment 20 of the rest 16 on the support 11 to permit rotation of the distal end of the humerus, which may be indicated, whereby to secure proper alignment of the fractured bone.

In use the base is adjusted on the side of 25 the patient adjacent the injured arm and the arm rest is attached to the support 11 in accordance with the particular arm that is injured. After the injured arm is placed on the arm rest, the support 11 may be adjusted 30 to secure the proper angle thereof relatively to the base. The several straps are adjusted to assure the rigidity of the base on the patient's body. Thereafter the base remains in place and the arm is maintained in fixed 35 position.

What I claim is:

1. A surgical splint comprising a laterally convex base member having its middle portion concaved longitudinally and adapted to 40 be engaged upon either side of the human trunk the lower part of said middle portion being longitudinally convex to engage on either human hip, a support hinged to the base and an angular arm rest adjustably 45 carried by the base and being reversible end to end on the support, the rest being concaved transversely and being widest and convex longitudinally at the apex of the angle thereof.
- 50 2. A surgical splint comprising a base shaped to conform to the curvature of the side of the human body, a support hinged to the base, means to adjust the angularity of the support relatively to the base and an 55 angular one piece arm rest adapted to be secured at either end to the support, said rest being concave transversely and tapering from its central portion toward each end thereof said central portion being also convex longitudinally.

In witness whereof I have hereunto subscribed my name.

JOE J. ETTINGER.
